UNITED STATES PATENT OFFICE.

CHARLES ROGERS, OF ALLEGHENY, ASSIGNOR TO HIMSELF AND JAMES A. HUTCHISON, OF PITTSBURG, PENNSYLVANIA.

IMPROVEMENT IN STEAM-ENGINE VALVE-GEAR.

Specification forming part of Letters Patent No. 140,309, dated June 24, 1873; application filed January 6, 1873.

To all whom it may concern:

Be it known that I, CHARLES ROGERS, of Allegheny City, in the county of Allegheny and State of Pennsylvania, have invented a new and useful Improvement in Steam-Engine Valve-Gear; and I do hereby declare the following to be a full, clear, and exact description thereof, reference being had to the accompanying drawing making a part of this specification, in which—

Figure 1 is a side elevation of an engine and pump, illustrative in part of my improvement. Figs. 2 and 3 are detached views in perspective, illustrative of the improved devices employed in the steam-chests. Fig. 4 shows an enlarged vertical section of a part of the reversing devices taken in the plane of the axial line of the valve-stem; and Fig. 5 shows in perspective one of the wedge-ended blocks employed in Fig. 4.

Like letters of reference indicate like parts in each.

In the class of steam-engines commonly known as direct-acting engines, where a fly-wheel and crank are dispensed with, some means specially designed for the purpose are ordinarily required to complete the throw of the valve. My invention relates to means for accomplishing this end, and also to means for adjusting the valve to its seat and relieving it of a portion of the downward pressure of the steam.

To enable others skilled in the art to make and use my improvement I will proceed to describe its construction and mode of operation.

A represents an ordinary steam-cylinder. It has the usual piston, the stem A' of which extends to and is connected with a pumping-piston in the pump C, or connection may be made with any other device or machine for communicating power. The engine is of the class known as direct-acting. B is the steam-chest. The valve b is operated back and forth in the manner of the ordinary slide-valve by the valve-stem b¹. On this stem are the usual tappet-nuts b². The piston-stem A' carries the usual tappet-arm g. On each side of the tappet-arm g I secure a spring, g', the upper bearing-end of which will come between the upper end of the tappet-arm g and the nut b² on that side. The end of the valve-stem b¹ op-

posite the valve b carries a piston, f, Fig. 4, on the upper and lower faces of which are the teeth e, which are of such form as to give a double incline—that is, an incline from the apex each way in the direction of the motion of the stem b¹. The box or case D which contains these devices also contains the blocks D', each of which has a wedge-shaped end, as at d, and such ends bear against the teeth e and are pressed against such teeth by springs d' or other like means. The piston f is capable of a limited longitudinal motion in its case, and is cushioned at its opposite ends on elastic seats or cushions f'.

In operation the movement of the main piston brings one of the springs g' against its nut b². The spring yields partially or wholly, till, by the force thus brought to bear, the valve b receives that part of its motion which is ordinarily given to it directly by the tappet-arm itself. The devices are so adjusted with reference to each other that at this point the apexes of the teeth e will be brought against or carried past the apexes of the wedge-shaped ends d, the inclines of the two sliding on each other and the springs d' yielding to allow the retrocession of the blocks D. As soon as these apexes come against or pass each other the elasticity of the spring g' comes into action to force the valve b forward through the remainder of its throw. The blocks D offer then no resistance, but, through the springs d', actually co-operate with the springs g' in completing the throw of the valve, and the springs d' (of any desired form) may be made of such rigidity and elasticity that, in connection with suitable devices for lessening the friction of the inclines on each other, they will perform the function of the springs g', and in such case the latter may be dispensed with; also, a single tooth, e, with a single wedge-ended block, D, may be used, as this will secure the end in view, though less perfectly than when the devices are duplicated, as in the drawing. The valve-chest B and the slide-valve b are provided with the usual arrangement of steam and exhaust ports. To relieve the valve of a portion of the downward pressure of the steam, or, in other words, to balance the valve, as it is called, I cover it with a top plate, a, which I cause to rest with the greater part of the

downward pressure, which it exerts from the pressure of the steam thereon, on the side plates *c c*. The upper edges of these side plates are slightly inclined and bear against corresponding inclines in the top plate *a*, as shown at *c'*, Fig. 2, so that while the top plate *a* is always horizontal, it may be raised or lowered vertically by setting the side plates *c* forward or back, which is done by means of set-screws *c'*. By this means the top plate *a* is made to cover the valve as tightly as may be desired, and at the same time the greater part of the downward pressure is sustained by the side plates *c*; and, as the valve or its seat or the under side of the top plate wears away, the devices may be readjusted at pleasure without even necessarily stopping the engine for that purpose.

I prefer that the steam-ports should extend up through the valve, and that at the end of the valve-stroke the steam-port at that end should be uncovered, as at *s*, so that the cylinder shall take steam both under the valve, as at *s'*, and also from above at *s*. I thus secure a large port-opening with a short throw.

To keep the top plate *a* down I arrange between it and the steam-chest cover *a'* a pressure-spring, *e'*, of any suitable construction. Its operation is too obvious to require description.

I am aware that spiral springs unconnected with the tappet-arm have been arranged on the valve-stem at the tappet-nuts. The construction hereinbefore described is superior, however, in that the springs are more easily

removable and renewable, and their elasticity can be more accurately adjusted with reference to the pressure required to complete the throw of the valve.

What I claim as my invention, and desire to secure by Letters Patent, is—

1. The inflexible tappet-arm *g* having the springs *g'* attached thereto, in combination with the tappet-nuts, piston-stem, and valve-stem of a direct-acting engine, arranged substantially as set forth.

2. The valve-stem *b'* carrying and operating a piston, *f*, in the box or case *D*, such piston having one or more double inclines, *e*, in combination with the wedge-shaped end or ends *d* of one or more blocks, *D'*, and a spring or springs for pressing the block or blocks to their work, the parts being relatively arranged substantially as and for the purposes set forth.

3. The arrangement inside the steam-chest and outside the valve of the top plate *a* and adjustable side plates *c*, making with each other an inclined joint, *c'*, substantially as set forth.

4. The arrangement inside the steam-chest and outside the valve of the top plate *a*, whereby, in connection with ports *s s'*, the valve will take steam past the end of the top plate, substantially as set forth.

In testimony whereof I, the said CHARLES ROGERS, have hereunto set my hand.

CHAS. ROGERS.
